R. FOX,
FOLDING IRONING BOARD,
APPLICATION FILED JAN. 20, 1920.

1,340,265.

Patented May 18, 1920.

Inventor:

Ralph Fox
By Abram Schwartz Atty.

UNITED STATES PATENT OFFICE.

RALPH FOX, OF WOOSTER, OHIO.

FOLDING IRONING-BOARD.

1,840,265.

Specification of Letters Patent. Patented May 18, 1920.

Application filed January 20, 1920. Serial No. 352,913.

To all whom it may concern:

Be it known that I, RALPH Fox, a citizen of the United States, residing at Wooster, in the county of Wayne and State of Ohio, 5 have invented a new and useful Folding Ironing-Board, of which the following is a specification.

My invention relates to improvements in folding ironing-boards and its primary object is to provide improved means for supporting the free end of the ironing-board, whereby more room is afforded underneath the same; second, to provide better and stronger means for supporting the free end 15 of said board in use, and third, to simplify the folding without diminishing the strength of the apparatus; and it consists of the novel features and combination of parts as hereinafter fully set forth and as 20 stated in the appended claims.

My invention is illustrated by the accompanying drawings, in which similar letters and figures of reference indicate like parts. Referring thereto, Figure 1, is a side elevation of an ironing-board embodying my invention; Fig. 2, is a like view of the same folded together, and these appear to be sufficient for illustration. In the drawings, A is the ironing-board proper, B is a diagonal 25 support, and C is a vertical support composed of two vertical members framed together, and provided with feet 11 adapted to stand upon a floor; each of said members is provided with a lateral projection F at 30 its upper end, adapted to receive thereunder a horizontal latch E. D is a small ironing-board mounted on a rotatable support d and arranged to swing sidewise over the board A, and to be removable therefrom at pleasure. This feature, however, is not new, and 35 no specific claim is made thereto by me. The novel supporting and folding devices cooperate by means of a pair of strap-hinges H and G, one of which connects the upper 40 end of the diagonal support B to the adjacent standard C at a point near the under side of the adjacent end of the board A, and so as to engage a notch 2 therein, by the upper end 3 of the diagonal support B—the 45 latter being preferably constructed with a pair of bars in all respects alike and joined together, substantially as shown, and each of said bars is hinged in the manner, above set forth, to the respective adjacent standards C; the other hinge, G, is secured to a

cross-bar 4 which rests upon the upper side of the support B near its upper end, and to the under side of the board A, so that the latter rests upon the upper edge of said cross bar 4. The arrangement is such that when 60 the device is in folded position shown in Fig. 2, it may be readily brought into unfolded and operative position shown in Fig. 1 by simply lifting up the outer end a— of the board A, whereby the supports B and C will 65 automatically take the normal positions therein shown, by the action of the pair of hinges H and G on both sides of said supports, and the extended adjacent ends 5 of the board A will slip over the upper ends F of 70 the standards C sufficient to permit the latch E, shown in dotted lines E', to be swung sideways between the lateral projections F and 5 whereby the outer end a is firmly held in elevated position, and resting solidly upon 75 the hinged supports as aforesaid.

The mutual coöperation of said hinged members tightens the apparatus, and pressure upon the outer end a only serves to make the frame work more rigid. Removal 80 of the latch by swinging it outwardly in the direction of the arrow, and folding it on its end pivot around upon the upper side of the board A, permits the outer ends a and 1 to be folded in the direction of the arrows 85 at said points, automatically. Thus a strong, safe and rigid ironing-board is provided, having a larger opening underneath it, and more space is afforded for handling sewed-together garments than heretofore, 90 and the board and its supports may be more readily folded together.

I do not limit my claim to mere form, but it is subject to such modifications as are reasonably within its scope. 95

Having thus fully described my invention, what I claim as new and desire to secure by Letters Patent is—

1. In a device of the character described, the combination with an ironing board, of 100 a supporting frame comprising a pair of standards having lateral projections at their tops, said board having in its end slots receiving said standards, and a diagonal support intermediate said board and standards, 105 hinged to both at and near its upper and adjacent end, and means insertible between said projections and said board for latching the front end of said board to said standards, substantially as set forth. 110

2. In a device of the character described, the combination with an ironing-board, of a supporting frame, comprising a pair of standards and a diagonal support intermediate said board and said standards, said diagonal support hinged to said board and to said standards at its junction therewith respectively, said board and standards having overlapping and spaced projections respectively, and a latch adapted to engage

between said projections, substantially as set forth.

In witness whereof I hereunto set my hand this 20th day of September, 1919, in presence of two witnesses.

RALPH FOX.
